UNITED STATES PATENT OFFICE.

GEORGE NEILSON, OF BOSTON, MASSACHUSETTS, ASSIGNOR TO HIMSELF AND NEHEMIAH HUNT.

CAST-IRON PAVEMENT.

Specification of Letters Patent No. 12,755, dated April 17, 1855.

To all whom it may concern:

Be it known that I, GEORGE NEILSON, of Boston, in the county of Suffolk and State of Massachusetts, have invented a new and useful Improvement in Cast-Iron Pavements; and I do hereby declare that the same is fully described and represented in the following specification and the accompanying drawings, letters, figures, and references thereof.

Of the said drawings, Figure 1 denotes a top view of one of my improved pavement blocks. Fig. 2 is a side view of it. Fig. 3 is a transverse section of it. Fig. 4 is a top view 15 of a block formed as will be hereinafter described. Figs. 5 and 6 exhibit a portion of a pavement laid with blocks of the said kinds.

This block consists of a cast iron box A, 20 closed at top and open at bottom and having a perimeter of thirty square pieces, *a*, arranged as shown in Fig. 1, and made by similar hexangular prisms disposed with respect to each other as shown at *b*, *b*, *b*, &c., in 25 the said figure.

This method of making a block has an important advantage over a block which is formed by six hexangular prisms or hexagons, *c*, *c*, *c*, disposed around a central prism 30 or hexagon, *d*, as seen in Fig. 4, for when

the first kind of blocks are laid together in a pavement, each of them where it abuts against an adjacent block will be supported by a semi hexagonal projection and a corresponding recess—the same forming a much 35 better tie of the two blocks than results from combining blocks of the form shown in Fig. 4.

I do not claim a pavement block of a hexagonal form; nor with a perimeter formed 40 by six hexagons disposed around a common or central hexagon as shown in Fig. 4, but

What I do claim is—

Making a paving block with a perimeter of thirty faces arranged as shown in Fig. 1, 45 and formed by sixteen hexagons or hexagonal prisms disposed with respect to one another as therein represented—the same enabling such a block, where it abuts against a contiguous block when laid in a pavement, to be supported laterally by a semi-hexagonal projection and recess as described.

In testimony whereof, I have hereunto set my signature this twelfth day of February A. D. 1855.

GEORGE NEILSON.
